UNITED STATES PATENT OFFICE.

WILLIAM H. GROGAN, OF NEW YORK, N. Y., ASSIGNOR TO ELMS AND SELLON, INC.,
OF NEW YORK, N. Y., A CORPORATION OF NEW YORK

DESIGN FOR TEXTILE FABRIC USED FOR DRAPERIES.

Application filed May 19, 1925. Serial No. 13,492. Term of patent 3½ years.

To all whom it may concern:

Be it known that I, WILLIAM H. GROGAN, a citizen of the United States, residing in the city, county, and State of New York, have invented a new, original, and ornamental Design for Textile Fabric Used for Draperies, of which the following is a specification, reference being had to the accompanying drawing, forming part hereof.

The drawing is a face view of a piece of textile fabric showing the new design.

I claim:

The ornamental design for textile fabric used for draperies as shown.

WILLIAM H. GROGAN.
